UNITED STATES PATENT OFFICE.

WARREN FRASIER, OF HARRISBURG, PENNSYLVANIA.

METHOD OF MAKING SHOES.

1,207,529.

Specification of Letters Patent.

Patented Dec. 5, 1916.

Application filed December 22, 1915. Serial No. 68,266.

To all whom it may concern:

Be it known that I, WARREN FRASIER, a citizen of the United States of America, and resident of Harrisburg, in the county of 5 Dauphin and State of Pennsylvania, have invented certain new and useful Improvements in Methods of Making Shoes, of which the following is a specification.

This invention relates to boots and shoes 10 and particularly to means for securing soles to uppers.

An object of this invention is to provide 15 novel means for increasing the strength and durability of the joint between the uppers and soles of shoes without impairing the wearing qualities of the sole and without exposing it to view, the securing means which are relied upon as augmenting or increasing the stability of the means for joining the 20 parts together.

A still further object of this invention is to provide novel means for attaching a single sole to the upper in which the upper is fastened outward and fastened to an extension of the sole.

In carrying out my invention, I provide means for slitting the edge of the sole, preferably at a depth of one fifth of its width, the said slit being near the upper surface of 30 the sole and I provide means whereby rivets may be applied which penetrate the upper and sole to the point at which it is slit, and I furthermore provide means for clenching the rivets without appreciably bending the 35 lower portion of the sole with respect to the main portion thereof, it being only necessary to form a clearance in which a relatively thin anvil may travel against which the ends of the rivets abut during the clenching operation.

With the foregoing and other objects in view, the invention consists in the details of construction, and in the arrangement and combination of parts to be hereinafter more 45 fully set forth and claimed.

In describing the invention in detail, reference will be had to the accompanying drawings forming part of this specification wherein like characters denote corresponding parts in the several views, and in which—

Figure 1 illustrates a view in perspective

of a shoe, the sole and a portion of the upper being shown in section to depict the relation of parts; Fig. 2 illustrates a sectional view 55 of a fragment of the upper and sole; and Fig. 3 illustrates a sectional view on the line 3-3 of Fig. 2.

In these drawings 4 denotes the upper, the edges 5 of which are lasted outward to 60 lie on the surface of the sole 6 at its edge, the said sole being provided with a slit 7 extending inwardly from its edge and preferably at a distance from its upper edge equal to one-fifth of the thickness of the 65 said sole, the said slit being designed for the purpose of receiving an anvil against which the ends 8 of staples 9 may be forced for the purpose of clenching the said ends of the staples. By reference to the drawing, it will be apparent that the staples extend only partially through the sole and they are entirely obscured or hidden from view, and it is furthermore apparent that a great percentage of the thickness of the sole may 70 be worn away before the staples are encountered.

After the upper has been secured to the sole in the manner indicated, a welt 10 is applied so as to make the appearance more 80 finished and this welt is preferably secured in place by stitching 11, which is a well known and common expedient for accomplishing this result.

The fact that means have been provided 85 for stapling a portion of a sole to an upper without materially flexing the said sole makes it apparent that one of the novel features of the invention is the position of the slit with relation to the upper and lower 90 surfaces of the sole, the advantages of which would be apparent from those skilled in the art since it increases the wear of the sole as stated before the staples are exposed or affected by coming in contact with the surfaces which the sole encounters when the shoe is used.

I claim:

1. A method of making shoes including the joining of a sole and an outwardly lasted 100 upper comprising the slitting of the sole inwardly from its edge at a point above where the lower part of the sole will flex and stapling the upper to the sole, clench-

ing the staples at the slit of the sole and in securing a welt to the outwardly extending portion of the upper.

2. A method of making shoes including the joining of a sole and an outwardly lasted upper, comprising the slitting of the sole inwardly from its edge at a point where when slit part of the sole below the slit will

not flex; stapling the upper to the sole, and clenching the staples at the slit of the sole. ¹

In testimony whereof, I hereunto affix my signature in the presence of two witnesses.

WARREN FRASIER.
